(57) **CLAIM**

The ornamental design for a baby carrier, as shown, and described.

DESCRIPTION

FIG. 1 is a right perspective view of the baby carrier showing my new design;

FIG. 2 is a left perspective view of the baby carrier;

FIG. 3 is a front view of the baby carrier;

FIG. 4 is a right view of the baby carrier;

FIG. 5 is a rear view of the baby carrier;

FIG. 6 is a left view of the baby carrier;

FIG. 7 is a top perspective view of the baby carrier, the top of the baby carrier being rotated slightly backward relative to, for example, FIG. 4; and,

FIG. 8 is a bottom perspective view of the baby carrier, the top of the baby carrier being rotated slightly backward relative to, for example, FIG. 4.

The short-long-short broken lines illustrate surface shading of claimed surfaces. The evenly dashed broken lines illustrate portions of the baby carrier that form no part of the claimed design.
